UNITED STATES PATENT OFFICE.

WILLIAM M. YOUNG, OF HARRISBURG, PENNSYLVANIA.

TELEPHONE ATTACHMENT.

Application filed May 23, 1927. Serial No. 193,549.

My present invention, in its broad aspect, has reference to improvements in attachments for telephones, and it is designed to accomplish the following principal results; 5 first, to reduce the length of the flexible connection, or cord, to the receiver and to place a constant load upon the said cord when the receiver is removed from the hook and placed at the ear thereby to discourage 10 the present tendency to prolong frivolous calls and; second, to complete a contact or connection to "central" only when the receiver cord is placed under a load as when the receiver is placed to the ear, and as a 15 corollary to this function causing the connection or contact to be broken when the receiver is negligently set down, i. e., not returned to the hook.

It has been found that considerable disadvantage results from the use of multi-party lines at the present time due to needless prolongation of calls by persons who have no urgent messages to impart or important business to transact. By placing a load upon 20 the cord to the receiver when the receiver is placed at the ear such lengthy and frivolous conversations are discouraged. Hence, the first result above enumerated is an important one. By way of explaining the far reaching 25 advantages of the second result, it is pointed out that when a receiver is negligently left from the hook the line is reported "busy" or "out-of-order" when one tries to communicate with the party whose receiver 30 is not hung up. This results in needless expenditure of time and money on the part of the telephone company, and results in confusion on the part of one trying to complete a call. Hence by permitting the contact or 35 connection to be made only when the cord is placed under an intentional load, as by withdrawing it to place the receiver at the ear, simply placing the receiver on the table, on which the telephone rests, for instance, 40 will not result in having the line reported "busy" or "out-of-order."

Furthermore, my attachment may be incorporated in conventional telephone receiver and transmitter units without in any 45 way modifying their construction, it being merely necessary to utilize the ordinary base brackets to mount certain elements of my device, the conventional bushing of the transmitter column for other elements, and the 55 ordinary vertical standard of the hook-switch contact spring for others. Since

types of receivers and transmitter units vary widely a simple desk set is illustrated in the drawings conventionally, and it is pointed out that any type may be used, as for instance, magneto wall sets; common-battery sets; automatic sets or; permanent magnet and direct-current receivers.

Other and equally important objects and advantages will become apparent as the description of my invention proceeds, but while I have in the present instance defined for the sake of illustration an article of a certain specific form, it will be understood that I do not desire to limit myself except as 60 65 70 may be indicated by the scope of the claims appended hereto and forming a part of this specification.

In the drawings wherein is illustrated an embodiment of my invention;—

Figure 1 is a detail view of my device assembled in a conventional type of telephone receiver and transmitter set,

Figure 2 is a detail view of my device when in position to complete a connection, 80 and

Figure 3 is a detail of the switch-connection when a receiver is inadvertently left off the hook.

In the drawings wherein like characters 85 of reference are used to designate like or similar parts throughout the several views:

A designates the transmitter of a telephone set, B the column, C the hook-switch, D the receiver, E the switch contact, F the 90 switch-contact supporting standard, G the base, H the receiver cord, and J one of the base brackets. All of the foregoing parts are illustrated conventionally and are common to many types of telephone sets although in some instances the arrangement thereof is slightly different. These parts 95 are not within my inventive concept.

Ordinarily the connection is broken or made by placing or removing the receiver D 100 from the hook-switch C, and the cord H is sometimes several feet in length.

My invention embodies reducing the length of the cord H and attaching the inner end thereof to a properly insulated 105 clip (1) which is attached to one end of a spring (2), the other end of which is attached to the conventional base bracket J of the set. When the spring (2) is retracted as in Figure 1 and the receiver D on the hook some slack as at (3) is permitted in the cord, and the spring when extended, as 110

in Figure 2, allows the receiver to be placed to the ear but exerts a load on the cord H which discourages prolonged and frivolous conversations.

5 Attached to a convolution of the spring (2) somewhere near the end of the spring attached to the bracket J is one end of a wire or strand of material (4) which passes upwardly over an anti-friction roller (5) and 10 into a fibre or insulating tube (6) in the hollow column B. The other end of the wire (4) passes over a roller (7) and engages the switch contact E. The tube (6) is supported by brackets (8) on the switch- 15 contact standard F, and the roller (7) is mounted on a bracket retained by the screws which hold the switch contact in place. The roller (5) is supported in a bracket (9) which is retained in place preferably by a 20 screw (10) which may, and preferably does, engage in the bushing which holds the column in the base.

The wire (4), when the spring (2) is retracted as in Figure 1, normally holds the 25 switch-contact E from engagement with the hook-switch C in which case there is no connection with "central." Upon removing the receiver D and placing it to the ear the spring (2) is extended and consequently the 30 wire (4) is relaxed (as in Figure 2) which permits the switch-contact E to engage the hook-switch C and complete the circuit or connection. This is the position of the parts when the line is being used. However, suppose the party fails to hang up the receiver D. Such being the case the cord H is relaxed and the spring (2) is retracted to 35 pull the wire (4) to again break the connection, as shown in Figure 3. Consequently 40 when one fails to hang up the receiver the line is not reported "busy" or "out-of-order" and much confusion and loss of time and money is prevented.

Where required the parts of my invention 45 are formed of insulating fibre, and in order to prevent breaking of the parts, the clip (1) is formed with a collar (11) which prevents its withdrawal through the cord opening (12) in the base. Or, a similar result 50 may be accomplished by simply enlarging the clip so that it cannot pass through the opening. It is believed that the operation and advantages of my invention will be apparent from the foregoing, but attention is 55 invited to the fact that it may be quickly and cheaply manufactured from stock parts, and that it may be applied to ordinary telephone sets without in anyway changing or modifying them.

60 While in the foregoing there has been illustrated in the drawings and described in the specification such combination and arrangement of elements as constitute the preferred embodiments of my invention, it is 65 nevertheless desired to emphasize the fact

that interpretation of the invention should only be conclusive when made in the light of the subjoined claims.

I claim:

1. The combination in a telephone receiver 70 and transmitter set having a switch-contact, a hook-switch, and a receiver, of a receiver cord, a spring engaging the same, and a connection between the spring and the switch-contact whereby when the receiver 75 cord is pulled out to extend the spring the connection is relaxed to permit the switch-contact to engage the hook-switch.

2. The combination in a telephone receiver 80 and transmitter set having a switch-contact, a hook-switch, and a receiver, of a shortened receiver cord, a spring engaging the same and normally retracted when the receiver is on the hook-switch and extended 85 when the receiver is placed to the ear, and a connection between the spring and the switch contact whereby when the receiver cord is pulled out by removing the receiver from the hook-switch to the ear, the connection is relaxed to permit the switch contact 90 to engage the hook-switch.

3. The combination in a telephone receiver 95 and transmitter set having a switch contact, a hook-switch, and a receiver, of a shortened receiver cord, a spring engaging 100 the same and normally retracted when the receiver is on the hook-switch, a connection between the spring and the switch contact, said spring adapted to be extended to relax the connection when the receiver is placed to the ear thereby to complete the contact between the switch contact and the hook-switch, and retracted when the receiver is placed on a support for the set thereby draw 105 the connection to tract the switch-contact to break the contact upon failure to properly replace the receiver on the hook-switch.

4. The combination in a telephone receiver 110 and transmitter set having a switch contact, a hook-switch, and a receiver, of a spring connection between the receiver cord and the switch-contact and effective to break the contact between the hook-switch and switch-contact when the receiver is placed on the hook-switch or misplaced to one side 115 of the set, but normally operative to permit completion of the circuit when the receiver is placed to the ear.

5. The combination in a telephone receiver 120 and transmitter set having a base, a standard, a switch-contact, a hook-switch, and a receiver, of a spring connection between the receiver cord and the switch-contact and effective to break the contact between the hook-switch and the switch-contact when the receiver is placed on the hook-switch or misplaced to one side of the set, but normally operative to permit completion of the circuit when the receiver is placed to the ear, 125 and all of said parts except the hook-switch, 130

and the receiver and a portion of the receiver cord being housed in the base and standard of the set.

6. In a telephone set, means for tensioning the receiver cord when the receiver is placed to the ear, and breaking the connection when the receiver is not returned to the hook-switch, said means including a spring engaging the cord at one of its ends, and at

a point adjacent its other end connected with 10 the switch contact.

7. The device as defined in claim 6, and the receiver cord being shortened to place the spring under tension when the receiver is placed to the ear. 15

In testimony whereof, I affix my signature hereunto.

WILLIAM M. YOUNG.
